UNITED STATES PATENT OFFICE.

FRANK MARIAN COCKRELL AND JAMES MERCUB ROCKWELL, OF LIBERTY, MISSOURI

COVER FOR RADIATORS.

1,265,429.

Specification of Letters Patent.

Patented May 7, 1918.

Application filed April 10, 1917. Serial No. 161,037.

To all whom it may concern:

Be it known that we, FRANK M. COCKRELL and JAMES M. ROCKWELL, citizens of the United States, and residents of Liberty, in the county of Clay and State of Missouri, have invented a new and Improved Cover for Radiators, of which the following is a full, clear, and exact description.

Our invention relates to a protective cover for the radiators of automobiles, whereby to conserve the heat thereof in cold weather to aid in maintaining the water therein at the proper temperature for efficiency in the operation of the engine.

15 More particularly the invention relates to a cover adapted to be conveniently applied and secured to the radiator and provided with a curtain arranged to wind upon or be unwound from a spring roller supported by the cover, the curtain being adapted to close to any desired extent a front opening formed in the cover, whereby to expose more or less of the radiator section or completely blanket the same.

25 Our invention, in addition to novel means for securing it to the radiator, is characterized also by a novel relation between the cover and the curtain with its roller and by a pull cord arranged to be operated by the operator of the automobile from his seat; together with a novel arrangement of cord-operating and guiding means.

The invention will be particularly explained in the specific description following.

35 Reference is to be had to the accompanying drawings forming a part of this specification in which similar reference characters indicate corresponding parts in all the views.

40 Figure 1 is a front elevation of an automobile cover embodying our invention, showing the same applied to the radiator of an automobile;

Fig. 2 is a side elevation of the forward portion of an automobile, parts being broken away and others in section;

Fig. 3 is a perspective view of the cover detached, the curtain and its roller being omitted;

Fig. 4 is a transverse vertical section on the line 4—4, Fig. 3;

Fig. 5 is a side elevation of the means for controlling the pull cord of the curtain;

Fig. 6 is an enlarged sectional plan view on the line 6—6, Fig. 5, and indicating the steering post;

Fig. 7 is a fragmentary longitudinal ver-

tical section of a portion of a radiator with our improved cover thereon and certain cord-guiding means.

In carrying out our invention in accordance with the illustrated example, a cover designated generally by the numeral 10 conforms substantially to the frame and tanks of a radiator and is formed with a rearwardly extending flange 10^a. The flange 10^a is adapted to fit the radiator at the top and sides, said flange having an opening 11 at the top to accommodate the neck *a* of a radiator A. The cover and its flange have heat-retaining lining 12. The hood for the main part is flexible, being made of any suitable waterproof cloth, leather, or the like, and wherever required for strength or protection, the material is reinforced by metal strengthening elements, there being a metal plate 13 within the hood across the bottom and a metal rod or wire 13^a around the top and sides at the opening 18, which opening is of a shape to expose the radiating section or honeycomb *a'*.

At the rear edge of the flange 10^a of the cover, the same is provided with hooks 14 to engage the back of the radiator A. Also, provision is made for strapping down the front of the cover at the bottom at each side, there being shown for the purpose straps 15 which in practice may be secured to any convenient part of the automobile and are adapted to be adjusted by buckles 16 on short billets 17 secured to the front of the cover.

Below the opening 18 at each side we provide brackets 19 secured by rivets or otherwise to said cover, the brackets being adapted to receive the trunnions 20 of a spring roller 21 to which the curtain 22 is secured at its lower end so that the roller normally tends to wind the curtain. A pull cord 23 is secured to the curtain, said cord having operating means located within convenient reach of the operator. Preferably, the curtain controlling means are secured to the steering post B and extend through the dash board or equivalent part C of the automobile forwardly through the engine hood and through the radiator to the connection to the curtain. The controlling means includes a tubular fixture 24 having a longitudinal slot 25 and a slide 26 in said tube is provided with an operating knob or handle 27, the shank of which extends through the slot 25. The cord extends from the slide 26 through a tubular guide extension 28 in the lower

end of said tube. The tube is secured in position on the steering wheel or other convenient support, there being shown in the present example clamps 29 embracing the 5 tube near the top and bottom and having spring jaws clamped to the steering post B by clamp screws 31 on threaded studs, 30.

A tubular housing 33 extends through the engine hood D and is secured at its rear 10 end to the dash board C or other support and at its forward end to the radiator A. To the front end of the housing 33 a tubular extension housing 34 is secured and is adapted to pass through one of the air cells of the 15 radiating section or honeycomb a'. The connection between the housing 33 and the housing section 34 is effected by any suitable coupling 35. On the section 34 is a washer or washers 36 and at the front there- 20 of is a flange or washer 37 adapted to clamp the hood 10 against the front of the radiator. The element 37 carries brackets 38 or the like supporting a pulley 39 over which the pull cord 23 runs. The location 25 of the pulley 39 and its housing section 34 is at the top of the radiating section beneath a flap 40 on the hood 10 at the top, the said flap forming with the body of the hood a pocket at the front of the radiator into 30 which the upper end of the curtain will be drawn when the curtain is fully raised by a pull on the cord 23. The flap also serves to cover the pulley 39 and its attaching means at all times so as to prevent the same 35 from being conspicuous. The flap has a metal rod 41 bound therein at the bottom to stiffen the same and tends to maintain it in flattened position. The numeral 42 (Fig. 4) indicates a transverse hole through the 40 cover 10 at the top for the passage of the housing section 34. The curtain 23 is held raised to different degrees by engagement of the shank of the knob 27 in any one of several lateral recesses 32 provided along the 45 slot 25. With the knob 27 and slide 26 positioned at any one of the recesses 32, the reaction of the roller spring maintains the curtain taut at all times to prevent it from flapping and to prevent its deformation un- 50 der the air pressure due to the suction of

the fan or otherwise. The forming of the cover with its rear engaging hooks 14 and with the straps 15 at the lower corners permits of the cover being very quickly and securely fastened. The described construction 55 of the cover and the arrangement of the curtain together with its fastening means are designed with a view not to detract from the appearance of the automobile but rather to enhance the appearance. The mounting 60 of the curtain roller directly on the cover promotes simplicity in adjusting the whole in position and in removing the same. The arrangement of the housings 33, 34 with the described attaching means makes it possible 65 to apply the same to the automobile without any alteration in the radiator, the only change required to be made in the car being the boring of a hole in the dash board C to receive the rear end of the housing. 70

We wish to state in conclusion that although the illustrated example constitutes a practical embodiment of our invention, we do not limit ourselves strictly to the mechanical details herein illustrated, since 75 manifestly the same can be considerably varied without departure from the spirit of the invention as defined in the appended claim.

Having thus described our invention we 80 claim as new and desire to secure by Letters Patent:

A protective cover for radiators, the same being formed with an opening, and a curtain and curtain roller supported below the opening so that the curtain may have movement in an upward direction over said opening, a pullcord attached to the free edge of the curtain, guide means for the cord adapted to guide the same through a 85 radiator and a motor hood, said guide means including a pulley, and means to mount the pulley on a radiator near the top, and a flap on the cover near the top forming a pocket 90 into which the edge of the curtain may extend, the said flap being adapted to cover the said pulley when the latter is mounted in position. 95
